WEDGE-SHAPED DISPENSING CONTAINER
FOR POWDERY SUBSTANCES

Norman D. Giessen, Lakewood, Ohio

Application October 18, 1943, Serial No. 506,719

7 Claims. (Cl. 229—22)

1

This invention relates to dispensing containers for light, powdery materials, such as insecticide powders, for example. More particularly, the invention relates to a container of the type in which air pressure is used for the expulsion of the container contents, the air pressure being produced by depression of one or more of the container walls.

The invention has for its primary object the provision of a dispensing container which is of simple and inexpensive construction, and which is of such size and shape as to enable its contents to be conveniently and effectively directed to the desired regions without waste of such contents, as to enable it to effectively display, when on a counter or the like, the printed matter on its exterior wall surfaces, and as to enable a plurality of such containers to be compactly handled, shipped and stored.

A further object of the present invention is the provision of a dispensing container which is formed from a simple and inexpensive blank of cardboard or like material having parts which are readily and conveniently foldable to provide a chamber or compartment for the container contents, other parts which are readily and conveniently foldable to cover in whole or in part, said chamber or compartment after it has received such contents, and other parts which are readily and conveniently foldable to seal said chamber or compartment and complete the formation of the container.

A further object of the present invention is the provision of a container blank which is so constructed and arranged as to not only enable a chamber or compartment to be readily and rapidly formed by simple folding of certain parts of the blank but also, to enable said part to be self-maintaining in their folded relationship, thereby making it unnecessary to maintain the chamber or compartment by the use of adhesive or other independent fastening means.

Further objects of the present invention and some of its practical advantages will be referred to in or will be evident from the following description of one embodiment of the invention, as illustrated in the accompanying drawings, in which

Fig. 1 is a top plan view of the blank, in its initial flat condition, from which is formed the container constituting such embodiment;

Fig. 2 is a top plan view of said blank, after parts thereof have been folded to form a self-maintaining chamber or compartment and after other parts thereof have been folded to cover said chamber or compartment;

Fig. 3 is a longitudinal sectional view of the blank in its Fig. 2 condition, the view being on the line 3—3 of Fig. 2;

2

Fig. 4 is a perspective view of the container in its final form;

Fig. 5 is a sectional view thereof on the line 5—5 of Fig. 4;

Fig. 6 is a similar view on the line 6—6 of Fig. 4; and

Fig. 7 is a view of two containers in superposed complementary relation.

Before the container here illustrated is specifically described, for the disclosure of the present invention, it is to be understood that the invention here involved is not limited to the embodiment of the invention herein illustrated, as the invention obviously may take other forms. It also is to be understood that the phraseology or terminology herein employed is for purposes of description and not of limitation, the scope of the present invention being denoted by the appended claims.

The blank 10 from which the present container is formed is shown in Fig. 1 in its initial flat condition, said blank being made of deformable sheet material, such as cardboard of suitable grade and thickness and being produced by a simple and inexpensive stamping operation. As shown, the blank comprises a relatively elongated central strip and two opposed side wings which may be and here are identical. The central strip consists of a succession of integrally connected rectangular portions 11, 12, 13, 14 and 15. To facilitate the folding of four of such portions, in the manner hereinafter referred to, said central strip is transversely scored or indented between adjoining rectangular portions thereof, the fold lines so formed being designated by the reference numerals 16, 17, 18 and 19. Each side wing of the blank comprises two rectangular portions (those of one wing being designated by the reference numerals 20 and 21 and the corresponding portions of the other wing being designated by the reference numerals 20a and 21a) and one triangular portion (that of one wing being designated by the reference numeral 22 and the corresponding portion of the other wing being designated by the reference numeral 22a).

To facilitate the folding of these wing portions, in the manner hereinafter referred to, the wings are scored or indented to provide fold lines between adjoining portions thereof, the fold lines of one wing being designated by the reference numerals 24 and 25 and the corresponding fold lines of the other wing being designated by the reference numerals 24a and 25a. A fold line also is provided between the central strip and each wing, the fold line 26 lying between the central strip portion 13 and the triangular portion 22 of one wing and the fold line 26a lying between such central strip portion and the corresponding triangular portion 22a of the other wing.

The blank is first folded to provide a chamber

or compartment for the light, powdery material which is to constitute the container contents, said material being omitted from the drawings for simplicity of illustration. To that end, the wing portions 20 and 20a are swung inwardly, about their respective fold lines 24 and 24a. The portions 21 and 22 are next jointly bent upwardly about the fold line 26, and the portions 21a and 22a are jointly bent upwardly about the fold line 26a, so as to bring the portions 22 and 22a to substantially upright positions, substantially normal to the central strip 13. The portions 20 and 20a will then overlie the fold line 17 of the central strip. As here shown, the wing portions 20 and 20a are of such length or lateral extent that they meet at substantially the middle of the fold line 17, although they may be of greater or less length, if desired. Inasmuch as the fold lines 24 and 24a are inclined with respect to the central strip, and to the fold line 17 to which the fold lines 24 and 24a lead, the wing portions 20 and 20a lie when so folded in a plane forwardly inclined with respect to the plane of the central strip, as will be evident from Figs. 3, 4, 5 and 7.

Portions 11 and 12 are next jointly bent upwardly and slightly forwardly about the fold line 17, portion 12 being brought into engagement with the rear surfaces of the forwardly tilted wing portions 20 and 20a, and portion 11 being turned downwardly and slightly rearwardly, about the fold line 16, to bring it into engagement with the front surfaces of said wing portions 20 and 20a, which are thus sandwiched between the central strip portions 11 and 12 (see Fig. 3). The length of portion 11 is slightly greater than the vertical distance between the top of the forwardly tilted portion 12 and the central strip portion 13 therebelow (the vertical distance being indicated by the dotted line X in Fig. 3), and as a result, portion 11 must be forcibly swung rearwardly into engagement with the wing portions 20 and 20a. There is thus a frictional resistance to the forward movement of the lower "tucked in" edge of portion 11, which effects a locking together of the four portions (the central strip portions 11 and 12 and the wing portions 20 and 20a) which constitute the rear wall of the container.

The chamber or compartment thus provided (and which is self-maintaining by the "locked in" bottom edge of portion 11) is of prism-like contour, with a generally rectangular rear wall (heretofore referred to) and generally triangular side walls formed by the wing portions 22 and 22a. As the chamber or compartment is open at its top, it may be easily and conveniently filled with insecticide powder or other material of light, powdery nature.

Thereafter, the wing portions 21 and 21a, are swung downwardly about their respective fold lines 25 and 25a to cover, in whole or in part, the now filled chamber or compartment. As here shown, said wing portions are of such size as to jointly cover the entire chamber or compartment, as will be evident from Fig. 2. Although the width of these wing portions may be reduced, it is quite desirable for sealing purposes that their length be substantially the same as that of the chamber or compartment at its top, as will hereinafter more fully appear.

Adhesive material is next applied to the upper surfaces of the central strip portions 14 and 15, and as such portions project forwardly in substantially flat form from the chamber or compartment, the application of the adhesive to such surfaces can be easily, quickly and conveniently

effected. Thereafter, these adhesive coated forwardly projecting portions are swung upwardly and rearwardly (counterclockwise as viewed in Figs. 2 and 3) about the fold line 18, so as to bring portion 14 into contact with and securement to the upper surfaces of the wing portions 21 and 21a which cover the chamber or compartment. The end portion 15 is then bent downwardly, about the fold line 19, to bring it into contact with and securement to the rear surface of portion 12 which constitutes the outer part of the container rear wall.

This completes the formation of the container and the sealing of its contents, as will be readily understood. To permit ejection of such contents, in use thereof, either one or both of the front corners of the container may be cut away by the purchaser of the container, or such purchaser may notch the front edge of the container at any place along such edge to provide a discharge opening. To indicate the desirability of discharging the contents of the container from its front edge, a red dot 30 may be placed at each end of such edge and a similar dot 31 may be placed at the middle of such edge, all on the upper surface of portion 14, as shown in Figs. 1 and 4. The container contents are expelled, of course, by air pressure produced by depression of one or more of the container walls, such as by simultaneous depression of its flat bottom wall and its sloping top wall, all in a manner which will be readily understood.

The shape of the container is such that it can be easily and conveniently grasped and its contents effectively directed, without waste of such contents, to the desired areas. Moreover, its shape enables printed or advertising matter on its exterior surfaces to be effectively displayed when the container is positioned on a counter or the like, and as the blank from which the container is made has an initial flat form, it is a simple matter to print on that surface thereof which constitutes the exterior surfaces of the container. Further, its shape enables a plurality of containers to be compactly handled, shipped and stored, as indicated by Fig. 7 which shows two containers in superposed complementary relationship. The chamber or compartment of the container is formed by simple bending of certain parts of the inexpensive blank from which the container is formed, and the chamber or compartment is self-maintaining by the locking arrangement of its rear wall parts.

To those skilled in the art to which the present invention relates, further features and advantages of containers embodying the present invention will be evident from the foregoing description of one such embodiment.

What I claim is:

1. A container of the character described, comprising a generally rectangular bottom wall, a pair of generally upright side walls having downwardly and forwardly inclined top edges, a generally rectangular rear wall having an upwardly and forwardly inclined outer portion and a downwardly and rearwardly inclined inner portion, said side walls at their rear ends being substantially of the same height as that of said rear wall and being provided on their rear end edges with inturned wings clamped between the inner and outer portions of said rear wall, the inner portion of said rear wall having a length greater than the vertical distance between its upper edge and the plane of said bottom wall, whereby the lower edge of said inner wall portion is frictionally held

against forwardly movement, and a top wall extending rearwardly and upwardly from the front edge of the bottom wall to the top edge of said rear wall.

2. A container of the character described, comprising a generally rectangular bottom wall, a pair of generally upright side walls having downwardly and forwardly inclined top edges, a generally rectangular rear wall having an upwardly and forwardly inclined outer portion and a downwardly and rearwardly inclined inner portion, said side walls at their rear ends being substantially of the same height as that of said rear wall and being provided on their rear end edges with inturned wings clamped between the inner and outer portions of said rear wall, the inner portion of said rear wall having a length greater than the vertical distance between its upper edge and the plane of said bottom wall, whereby the lower edge of said inner wall portion is frictionally held against forwardly movement, and a top wall extending rearwardly and upwardly from the front edge of the bottom wall to the top edge of said rear wall, said top wall having a depending portion in planar contact with and secured to the exterior surface of said rear wall.

3. A container of the character described, comprising a generally rectangular bottom wall, a pair of generally upright side walls, a generally rectangular rear wall having an upwardly inclined outer portion and a downwardly inclined inner portion, the inclination of said rear wall portions causing their upper edges to overlie said bottom wall, said side walls adjacent said rear wall being substantially of the same height as that of said rear wall and being provided on their end edges with inturned wings clamped between the inner and outer portions of said rear wall, the inner portion of said rear wall having a length greater than the vertical distance between its upper edge and the plane of said bottom wall, whereby the lower edge of said inner wall portion is frictionally held in place, said side walls also being provided with inturned top portions of substantially the same length as that of said side walls, and a top wall overlying and secured to the inturned top portions of said side walls.

4. A container of the character described, comprising a generally rectangular bottom wall, a pair of generally upright side walls, a generally rectangular rear wall having an upwardly inclined outer portion and a downwardly inclined inner portion, the inclination of said rear wall portions causing their upper edges to overlie said bottom wall, said side walls adjacent said rear wall being substantially of the same height as that of said rear wall and being provided on their end edges with inturned wings clamped between the inner and outer portions of said rear wall, the inner portion of said rear wall having a length greater than the vertical distance between its upper edge and the plane of said bottom wall, whereby the lower edge of said inner wall portion is frictionally held in place, said side walls also being provided with inturned top portions of substantially the same length as that of said side walls, and a top wall overlying said inturned top portions of said side walls and having a depending portion in contact with and secured to the exterior surface of said end wall.

5. A container of the character described, comprising a generally rectangular bottom wall, a

pair of generally upright side walls having downwardly and forwardly inclined top edges, and a generally rectangular rear wall having an upwardly and forwardly inclined outer portion and a downwardly and rearwardly inclined inner portion, said side walls at their rear ends being substantially of the same height as that of said rear wall and being provided on their rear end edges with inturned wings clamped between the inner and outer portions of said rear wall, the inner portion of said rear wall having a length greater than the vertical distance between its upper edge and the plane of said bottom wall, whereby the lower edge of said inner wall portion is frictionally held against forwardly movement, said side walls also being provided at their top edges with inturned portions of substantially the same length as that of said side walls, and a top wall extending rearwardly and upwardly from the front edge of the bottom wall to the top edge of said rear wall and overlying and secured to the top portions of said side walls.

6. A container of the character described formed from a flat one-piece blank of sheet material, said blank having a central strip and opposed wings on opposite sides thereof, said central strip being foldable to provide a bottom wall and a top wall and a rear wall of reversely bent upwardly and forwardly inclined form, and said wings being foldable to provide a pair of upright side walls and a pair of side wall inturned rear and edge extensions for securement between the inner end portions of said reversely bent rear end wall and a pair of side wall inturned top edge portions for underlying relation with and securement to said top wall, the inner and outer portions of said rear wall being of the same length and their forward inclination serving to maintain the side wall extensions in clamped relationship therewith.

7. A dispensing container for light powdery substances and consisting of a single sheet of material bent to provide a generally rectangular bottom wall, a pair of substantially upright and generally triangular side walls, said bottom wall and said side walls each comprising a single thickness of such material, a generally rectangular top wall inclined upwardly and rearwardly from the front edge of said bottom wall and comprising two thicknesses of such material, a generally rectangular rear wall inclined upwardly and forwardly from the rear edge of said top wall and comprising at least three thicknesses of such material, said walls defining a closed chamber of prism-like contour, and a discharge aperture for the contents of said container at the front edges of said bottom and top walls.
